The ornamental design for a miter bar, as shown and described.

DESCRIPTION

FIG. 1 is a front, top, left side isometric perspective view of a miter bar in accordance with my design;

FIG. 2 is a front elevation view thereof;

FIG. 3 is a rear elevation view thereof;

FIG. 4 is a top plan view thereof;

FIG. 5 is a bottom plan view thereof;

FIG. 6 is a left side elevation view thereof; and,

FIG. 7 is a right side elevation view thereof.

The broken lines illustrate portions of the miter bar which form no part of the claimed design.

The “dash-dot” broken lines in FIGS. 1-5 are meant to show a symbolic break in the claimed design. Any portion which appears between the symbolic break lines forms no part of the claimed design.
